HOUSING FOR A MEAT GRINDER, SALAD SHREDDER OR THE LIKE

Alfred W. Madl, Glendale, Wis., assignor to Oster Corporation, Milwaukee, Wis.

Filed July 5, 1974, Ser. No. 485,986

Term of patent 14 years

Int. Cl. D7—04

FIG. 1 is a perspective view of a housing for a meat grinder, salad shredder or the like showing my new design;

FIG. 2 is a front elevational view thereof;

FIG. 3 is a top plan view thereof;

FIG. 4 is a side elevational view of the side not shown in FIG. 1;

FIG. 5 is a rear elevational view.

I claim:

The ornamental design for a housing for a meat grinder, salad shredder or the like, as shown.
